FLUORESCENT LIGHT FIXTURE

Edward F. Zurawski, Chicago, Ill., assignor to Garden City Plating & Manufacturing Co., a corporation of Illinois

Filed Dec. 3, 1959, Ser. No. 58,538

Term of patent 14 years

(Cl. D48—23)

Fig. 1

Fig. 5

Fig. 2

Fig. 3

Fig. 4

FIG. 1 is a perspective view of a fluorescent light fixture showing my new design;

FIG. 2 is a side elevational view of the fixture;

FIG. 3 is a bottom elevational view of the fixture; and

FIG. 4 is an enlarged fragmentary cross sectional view of the fixture, taken along the line 4—4 of FIG. 2, showing the transparent bottom wall and translucent side walls;

FIG. 5 is an enlarged fragmentary perspective view as seen from the bottom of the lens member.

I claim:

The ornamental design for a fluorescent light fixture, substantially as shown.
